DESIGN FOR A FACE PLATE FOR MOTOR SIGNALS

John Reginald Chester Andrews, East Angus,
Quebec, Canada

Application January 31, 1935, Serial No. 55,158
In Canada January 17, 1935

Term of patent 14 years

To all whom it may concern:

Be it known that I, John R. Chester Andrews, a citizen of the Dominion of Canada, residing at East Angus, in the Province of Quebec, Dominion of Canada, have invented a new, original, and ornamental Design for a Face Plate for Motor Signals, of which the following is a specification, reference being had to the accompanying drawing, forming part thereof.

The figure is a front view of a face plate for motor signals, showing my new design.

The face plate is substantially flat and of no material thickness, with the cut-out portions extending through the plate, so that the rear side of the plate is substantially the same as the side shown in the drawing, with the exception that the cut-out portions would be shown in reversed position.

I claim:

The ornamental design for a face plate for motor signals, as shown and described.

JOHN REGINALD CHESTER ANDREWS.
